CLAIM

The ornamental design for a car tail light, as shown and described.

DESCRIPTION

FIG. 1 is a perspective view of a car tail light showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is another front elevational view in an alternate state of use thereof;

FIG. 10 is another front elevational view in an alternate state of use thereof;

FIG. 11 is another front elevational view in an alternate state of use thereof; and,

FIG. 12 is another front elevational view in an alternate state of use thereof.

The dash-dash broken lines in the drawings depict portions of the car tail light that form no part of the claimed design. The dash-dot broken lines shown in FIGS. 9-12 represent the illumination at the front surface of the car tail light and form no part of the claimed design.

1 Claim, 12 Drawing Sheets
